[57] CLAIM

The ornamental design for a hood for video monitor, as shown and described.

DESCRIPTION

FIG. 1 is a perspective view of a hood for video monitor showing my new design, the keyboard and monitor are shown in broken lines for illustrative purposes only and form no part of the claimed design;

FIG. 2 is a front elevational view thereof on an enlarged scale;

FIG. 3 is a top plan view thereof on an enlarged scale;

FIG. 4 is a rear elevational view thereof on an enlarged scale;

FIG. 5 is a bottom plan view thereof on an enlarged scale;

FIG. 6 is a side elevational view thereof on an enlarged scale, the opposite side being a mirror image.
